UNITED STATES PATENT OFFICE.

DAVID C. KLINE, OF ROCHESTER, NEW YORK, ASSIGNOR TO THE STEAM GAUGE AND LANTERN COMPANY, OF SAME PLACE.

TUBULAR LANTERN.

SPECIFICATION forming part of Letters Patent No. 364,420, dated June 7, 1887.

Application filed August 21, 1886. Serial No. 211,472. (No model.)

To all whom it may concern:

Be it known that I, DAVID C. KLINE, of the city of Rochester, in the county of Monroe and State of New York, have invented new and useful Improvements in Tubular Lanterns, of which the following is a specification.

This invention relates to an improvement in tubular lanterns, and has for its object to provide a simple, strong, and durable device for connecting the bail by which the lantern is carried to the tubular frame of the lantern. My invention consists, to that end, of the improvements which will be hereinafter set forth, and pointed out in the claims.

15 In the accompanying drawings, Figure 1 is a side elevation of the upper portion of a tubular lantern provided with my improvements. Fig. 2 is a vertical cross-section in line *x* *x*, Fig. 1. Fig. 3 is a partly-sectional elevation of the upper horizontal tube. Fig. 4 is a cross-section in line *y* *y*, Fig. 3. Fig. 5 is an elevation of the central vertical tube at right angles to Fig. 1. Fig. 6 is a view of the blank from which the horizontal top tube is formed. 25 Fig. 7 is a sectional view showing a slightly modified construction of the fastening.

Like letters of reference refer to like parts in the several figures.

30 A A represent the upper portions of the side tubes of a tubular lantern; B, the horizontal top tube connected with the upper ends of the side tubes by elbows *b*; C, the central vertical tube, and D the bell or concave plate attached to the lower end of the central tube, C.

35 E represents the wire bail, having its lower ends, *e e*, bent inwardly and inserted into ears or sleeves *ff*, formed on the horizontal top tube, B, and having their inner ends separated by a space, *f'*. These ears are formed 40 in one piece or integral with the horizontal tube B, by forming longitudinal depressions or sockets in the upper portion of the tube. The tube B is formed with its sleeves or ears *ff* of a single blank, G, as represented in Fig. 6. 45 The ears *ff* are formed by the central portions, *g g*, of the blank located on opposite sides of the central opening, *f'*. The portions *g g* are bent to form longitudinal sleeves on the top of the tube B, as represented in Figs. 3 and 4. 50 The longitudinal edge portions, *h h*, of the

blank are lapped over each other, forming a longitudinal bottom seam, as represented in the same figures, which is secured by soldering.

The blank is provided with notches *i i* in its longitudinal edges, which form an opening, *j*, in the under side of the tube B, by which the latter communicates with the vertical tube C. The lower portions, *ee*, of the bail are headed at their inner ends and inserted into the sleeves *f* before the longitudinal bottom seam of the tube is closed. The vertical tube C is provided near its upper end with side openings, *kk*, in which the horizontal tube B is inserted and secured by soldering. The upper end of the central tube, C, is closed by a cap, *l*.

55 The ears or sleeves *f*, being formed in one piece with the horizontal tube B, are not liable to become detached by heat or otherwise, as is the case when the ears are made separate from the pipe and secured by soldering. The 60 ears are easily and cheaply formed and serve to strengthen the horizontal tube, while they are neat in appearance.

65 It is obvious that a single sleeve or ear may be used for receiving both ends of the bail, as represented in Fig. 7, in which case the rigidity of the bail is relied on for holding the ends of the bail in the sleeve; but I prefer the construction represented in Fig. 3, in which two ears are used in connection with headed bail 70 ends.

75 I claim as my invention—

1. In a lantern, the combination, with the bail, of a horizontal top tube provided with a longitudinal sleeve formed in one piece with the tube and adapted to receive the bail, substantially as set forth.

80 2. In a lantern, the combination, with the bail, of a horizontal tube provided in its upper portion with a raised bail seat formed in one piece with the tube, substantially as set forth.

85 3. In a lantern, the combination, with the bail, of a horizontal top tube formed of a single blank and provided with a longitudinal sleeve formed in one piece with the tube and adapted to receive the bail, substantially as set forth.

90 4. In a lantern, the combination, with a central tube, C, having side openings, *k*, of a hori-

zontal tube, B, provided with a longitudinal sleeve formed in one piece with the tube and inserted in the openings k, and a bail seated in said sleeve, substantially as set forth.

5. In a lantern, the combination, with the horizontal tube B, provided on its upper side with two longitudinal sleeves, ff, formed in one piece with the tube, of a bail, E, having

its headed ends seated in said sleeves, substantially as set forth.

Witness my hand this 6th day of August, 1886.

DAVID C. KLINE.
